UNITED STATES PATENT OFFICE.

CLARENCE H. YOUNG, OF DORCHESTER, MASSACHUSETTS.

COUCH-BED.

1,247,777.

Specification of Letters Patent. Patented Nov. 27, 1917.

Continuation of application Serial No. 671,198, filed January 15, 1912. This application filed July 27, 1912. Serial No. 711,768.

To all whom it may concern:

Be it known that I, CLARENCE H. YOUNG, a citizen of the United States, and a resident of Dorchester, in the county of Suffolk and 5 State of Massachusetts, have invented an Improvement in Couch-Beds, of which the following description, in connection with the accompanying drawings, is a specification, like characters on the drawings representing like parts.

10 This invention relates to sectional extension beds or couches, one section of which is shifted relatively to another to provide a single or double bed, and among other objects provides a simple and effective means for so shifting one of the sections.

15 The character of the invention may be best understood by reference to the following description of an illustrative embodiment thereof shown in the accompanying drawing, wherein:

20 Fig. 1 is a perspective view of a portion of an illustrative extension bed embodying the invention;

25 Fig. 2 is a view of one end of the bed showing the sections in superposed relation;

Fig. 3 is a view similar to Fig. 2 showing one of the sections in the process of being shifted;

30 Fig. 4 is a view of the opposite end of the bed to that shown in Fig. 2;

Fig. 5 is a detail to be referred to; and

Fig. 6 is a section taken on line 6—6 of Fig. 5.

35 Referring to the drawing, the illustrative extension bed therein shown as embodying the invention comprises a stationary section A and a shiftable section B.

40 The stationary section has end frames, each comprising herein an arched tube 1, to which are secured an upper horizontal, angle cross bar 3 and a lower, horizontal, angle cross bar 5. The end frames may be connected by long stay tubes 7, 7 and a spring mattress 9 stretched between said angle bars 3, 3.

45 The shiftable section B has end frames, each comprising a tube 11 formed to provide

at one end thereof a leg 13. These legs may be connected by a long stay tube 15. Secured to the end frames are horizontal, cross bars 17 and angle cross bars 17^a. Between the latter is stretched a mattress 19.

50 To permit the shiftable section B to be adjusted relatively to the stationary section A it may be pivotally connected thereto by parallel links 21 and 23. To contribute to the rigidity of the structure the links 21 at the opposite ends of the bed may be connected intermediate their ends by a spreader 55 tube or bar 25 and at their lower ends by a tube or bar 27 fulcrumed in apertures in the lower horizontal angle bars of the stationary section.

50 By the above described arrangement of parallel links the section B when shifted will be lifted bodily and rocked to its retracted or extended positions. To effect this shifting movement it is necessary first to lift the section until the links have reached substantially vertical positions (Fig. 3). A slight further movement of the section will cause the links to rock past their dead centers and then gravity will complete the shifting movement.

75 I will now describe a simple and effective device for shifting the section B relatively to the section A. This device comprises an actuating member conveniently in the form of a lever 29 conveniently pivoted to the lower angle bar 5 at one end of the stationary section and provided with a treadle 31 enabling it to be readily operated by the foot. To connect this actuating lever with the movable section a chain 33 or other flexible connection is provided having one end connected to said actuating lever, preferably at a point intermediate its ends, and having its opposite end connected to an ear of a collar 35 on the spreader bar 25 referred to. This chain is passed over a pulley 37 (Figs. 5 and 6) in a shell 37^a conveniently secured to the upper horizontal angle bar 3 and at a point above the point of attachment of the chain to the spreader bar.

90 95 The section B in moving to its extended

position (Fig. 1) rocks slightly farther from the lower pivot point of the link 21 than when moving to its superposed position (Fig. 2). In order that the actuating lever 3 may be moved equally in shifting the section B to both positions as more fully hereinafter described, the pulley 37 is not placed directly above said pivot point, but is offset somewhat therefrom.

- 10 The points of connection of the chain with the treadle lever and spreader tube are somewhat offset on opposite sides of the plane of the arched tube of the end frame 1. To avoid objectionable wear on the chain or 15 pulley the latter is preferably placed so that its axis is somewhat inclined from a position perpendicular to said plane. This is conveniently effected by making a wall 37^b of the pulley shell 37^a wedge-shape (Fig. 6). 20 To equalize and assist the shifting of the movable section, the end of the stationary section opposite to the one provided with the shifting device described, may be provided with a helical spring 39 (Fig. 4) 25 having one end connected to the spreader bar 25 referred to and its opposite end formed to provide a hook 40 which may be inserted through holes in the end frame tube or be otherwise secured thereto. Preferably the upper end of this spring is connected to said tube at a point somewhat offset from a vertical line passing through the lower pivot point of the link 21 as in the case of the pulley at the opposite end. This 30 spring has not sufficient strength to initiate a shifting movement of the section B, but materially assists the movement after once initiated.

It may be supposed that it is desired to 40 adjust the section B from its extended position (Fig. 1) to its position for a single bed (Fig. 3). To this end the treadle 31 is pressed by the foot, thereby pulling the chain 33, rocking the links 21 and lifting the section B until said links pass vertical 45 positions (Fig. 3). In the course of this movement that portion of the chain extending between the pulley and spreader bar will swing about said pulley as a fulcrum until the links pass beyond their dead 50 centers or vertical positions when the chain will be swung further and dragged in an opposite direction, causing the treadle to reverse and be lifted back to its original 55 position. The foot is retained on the treadle during this reverse movement and pressed to check the final shifting movement of the section.

In other words, to shift the section the 60 treadle is rocked in one direction to initiate the movement, the pressure being sufficiently sharp to give the section enough "throw" or momentum to carry it past the dead centers of the links and then the treadle is gradu-

ally released to catch or check the momentum. Thus the treadle is successively depressed and elevated or moved in opposite directions for effecting a shift of the section B in one direction, and said treadle is operated in the same way to shift said section in both directions.

To extend the section B the treadle is pressed and checked as before, causing a similar shifting operation to occur with this difference; that the portion of the flexible connection between the pulley 37 and the link 21 will swing in an opposite direction to that which it had when the section B was shifted from its extended position to its position for a single bed.

The swing spring at the opposite end of the bed coöperates very advantageously with this treadle shift, since it is tensioned when the section B is moved to both its extended and superposed positions, and after the treadle has been pressed to initiate a shift movement the spring thus tensioned assists in shifting and checking the movement, decreases the work involved in shifting the treadle, and tends to equalize the movement of both ends of the section without twist or distortion thereof.

The treadle extends to a position at the side of the bed where it is conveniently accessible and readily operated and may always return to the same position irrespective of the direction which the shift section is moved.

While in the illustrative embodiment of the invention shown herein parallel links 100 are provided at each end of the bed for connecting the movable and stationary sections, in some instances the links 23 may be omitted. In such case the movable section will not be lifted bodily but will drag on the casters of the leg 13. However, I prefer the parallel motion since by it the drag is eliminated and injury to floors and carpets is thereby prevented.

The shifting device described is extremely 110 simple in construction and operation. By it there is no liability of displacing or rocking the stationary section off of its feet in the course of the shifting movement, since the pulley point of application of the chain 115 is relatively near the floor and substantially midway between the sides of the stationary section, and the pressure on the treadle is directed downward and tends to hold the stationary section fast on the floor.

In using the device it is found that a very nice control is provided since the movable section is both readily started from its positions of rest and is gradually checked as it approaches the completion of its shifting movements.

It will be understood that various modifications may be made in the construction

described without departing from the spirit and scope of the invention.

Having described one embodiment of the invention without limiting the same thereto, 5 what I claim as new and desire to secure by Letters Patent is:

1. In an extension bed, the combination of a plurality of sections and means including a foot operated member, the latter having provision for imparting an operator controlled lifting shift to one of the sections and checking at the will of the operator a falling shift of said section.

2. In an extension bed, the combination 15 of a plurality of sections, and means including a lever and a flexible power transmitting connection between said lever and one section for transmitting the power of the operator, first to impart a shifting momentum to said section and then to check 20 said momentum to check said section.

3. In an extension bed, the combination 25 of a plurality of sections, one shiftable relatively to the other, spring means tending to move and check the section in a shifting movement on receiving unidirectional downward pressure from the operator, and a member coöperating therewith both for initiating and checking said movement.

30 4. In an extension bed, the combination of a plurality of sections, a link at one end of the bed and a link at the opposite end of said bed for pivotally connecting said sections, a member connecting said links, a 35 spring connecting said member with one of said sections, a lever pivoted to an end of the bed, and a flexible connection extending from said lever to said member for initiating and checking a shifting movement of the pivoted section.

5. In an extension bed, the combination 45 of a plurality of sections, a link pivotally connected to said sections, an operating member, a guide on one of said sections, and flexible means connected to said link over 50 said guide to said operating member for extending or contracting the bed.

6. An extension bed comprising, in combination, a movable section, a stationary 55 section, said movable section being adapted to be moved relatively to the stationary section to an extended position and also to be retracted to a position immediately over the stationary section, a lever pivotally supported at one end to swing through a limited arc, and a connection between said lever and movable section whereby a swing of said lever in one direction initiates the extension of the movable section, and a substantially equal swing of said lever in the 60 same direction as before initiates the retraction of the movable section.

7. An extension bed comprising, in combination, a movable section, a stationary

section, the movable section being adapted 65 to be moved to an extended position and also to be retracted to a position immediately over the stationary section, a treadle adapted to be given a limited up and down movement, and connection between said 70 treadle and movable section whereby a downward movement of said treadle extends said movable section, and a substantially equal downward movement of said treadle retracts the movable section. 75

8. An extension bed comprising, in combination, a movable section, a stationary section, swinging means uniting said sections, a lever pivotally supported at one end, and a flexible connection between said 80 lever and swinging means adapted to shift the movable section to both extreme positions by like movements of said lever.

9. An extension bed comprising, in combination, a movable section, a stationary 85 section, a lever pivotally supported at one end to the stationary section, a flexible connection attached to said lever and connected with said movable section, and a pulley supported by the stationary section and sustaining said flexible connection, said parts being adapted to shift the movable section to both extremes of position by like movements of said lever. 90

10. In an extension bed, the combination 95 of a plurality of sections, one for extension or retraction movement relative to the other; and a lever operatively connected to both of said sections and movable by downward pressure to initiate either extension or retraction movement and subsequently movable in an upward direction by the operation of gravity on the moving section while the gravity actuated movement of the moving section is checked by a continuance of the downward pressure. 105

11. In an extension bed, the combination 110 of a plurality of sections, one for extension or retraction movement relative to the other; parallel links at each end of the bed and connecting said sections; and a lever operatively connected to said sections and movable by pressure in a given direction to initiate either extension or retraction movement and subsequently movable in a reverse direction by the operation of gravity on the moving section while the gravity actuated movement of the moving section is checked by a continuance of the pressure in said given direction. 115

12. In an extension bed, the combination 120 of a plurality of sections, one for extension or retraction movement relative to the other; and a foot lever operatively connected to both of said sections and movable by downward pressure to initiate either extension or retraction movement and subsequently movable in an upward direction by

the operation of gravity on the moving section while the gravity actuated movement of the moving section is checked by a continuance of the downward pressure.

5 13. In an extension bed, the combination of a plurality of sections, one shiftable relatively to the other for extension and contraction of the bed; and means for so shifting said section including a member op-

erable to extend said section and similarly 10
operable to retract said section.

In testimony whereof, I have signed my name to this specification, in the presence of two subscribing witnesses.
